UNITED STATES PATENT OFFICE.

JOSEPH PAUPA AND GUSTAV F. HOCHRIEM, OF CHICAGO, ILLINOIS.

COIN-CONTROLLED VENDING-MACHINE.

1,277,470.

Specification of Letters Patent. Patented Sept. 3, 1918.

Application filed October 5, 1917. Serial No. 194,871.

To all whom it may concern:

Be it known that we, JOSEPH PAUPA and GUSTAV F. HOCHRIEM, citizens of the United States, and both residing at Chicago, in the county of Cook and State of Illinois, have invented certain new and useful Improvements in Coin-Controlled Vending-Machines, of which the following is a specification.

10 This invention relates to improvements in vending machines, and more particularly to a vending machine in which is incorporated a game apparatus.

One of the objects of the invention is to 15 provide a combined game and vending machine wherein a coin-released elevator is manually operated to raise a single playing ball from the bottom or discharge end of the board to the upper or starting point.

20 Another object of the invention is to provide a freely movable ball receiving, guideway in combination with the game board, whereby the path of the playing ball is variable, depending upon the position which 25 the movable member happens to assume at the time the ball is dropped from the starting point.

A still further object of the invention is 30 to provide in combination with a vending mechanism and game mechanism, a signal device operated by the playing ball in the event the player is skilful enough to catch the ball in a manually, movable cup as it falls through the hazards of the bagatelle board.

A still further object of the invention is 35 to generally improve the vending machine and game and improve and simplify the apparatus as an entirety.

40 Still other and further objects will become readily apparent to those skilled in the art from a consideration of the following description and drawings wherein:

Figure 1 is a front elevation of the apparatus.

Fig. 2 is a rear elevation thereof with the door removed.

Fig. 3 is an enlarged, fragmentary, rear elevation of the coin-released actuating 50 mechanism.

Fig. 4 is a vertical sectional view on the line 4—4 of Fig. 2.

Fig. 5 is a horizontal sectional view on the line 5—5 of Fig. 1.

Fig. 6 is a bottom plan view of the vend- 55 ing mechanism.

Fig. 7 is a fragmentary, vertical sectional view on the line 7—7 of Fig. 4.

Fig. 8 is a fragmentary, vertical sectional view on the line 8—8 of Fig. 2. 60

Fig. 9 is a fragmentary sectional view on the line 9—9 of Fig. 2.

Fig. 10 is a fragmentary perspective view of the merchandise magazine illustrating the method of charging the same, and; 65

Fig. 11 is a fragmentary sectional view on the line 11—11 of Fig. 8.

The apparatus comprises in general an inclosing casing, the front face of which constitutes a bagatelle board and within 70 which is mounted a vending mechanism, the game apparatus and vending mechanism being conditioned for manual operation upon the depositing of a coin within a coin slot provided in the face of the machine. A lever extending through the front of the machine may then be actuated, operating the vending mechanism which supplies a package of merchandise, for example, a package of gum, and at the same time starts 75 the game in operation. The game apparatus comprises a vertical, bagatelle board with which co-operates a playing ball, elevated on the manual operation of the machine to the top of the board, from which it drops 80 through an opening onto the front face thereof and courses down through the various hazards. Across the front of the bagatelle board under the hazards is positioned 85 a horizontally slideable cup which may be manually operated by a knob extending through the front of the casing so that the operator, if skilful enough, may catch the ball as it falls from the hazards, in which 90 event the success of the player will be indicated by the ringing of a gong. The playing ball whether it is caught, or follows its usual course, returns to the bottom of the apparatus and into an elevator at the rear of the board in position for a subsequent operation. 95

One of the difficulties encountered with bagatelle boards of this character, is that the playing ball in starting from the top of the machine will usually follow a fixed course before striking the hazards, depending upon 100 whether the machine is mounted absolutely level or is slanted one way or the other. To eliminate this certainty of operation and 105

to make the catching of the ball more difficult, the first runway upon which the ball falls and which diverges from a central apex to each side is mounted upon a pivot and 5 carries a depending pendulum weight. A ball dropping upon the runway sets the pendulum in motion, oscillating the runway so that a subsequent ball will drop upon one side or the other of the runway depending 10 upon the position of the pendulum, thus introducing an uncertain factor into the operation of the game.

A coin dropped through a slot in the front of the machine conditions the coin release 15 device and serves as a key to connect the manually operable lever projecting from the front of the casing to the vending and game mechanism. Operation of the lever then delivers a package of merchandise and at 20 the same time actuates a ball elevator which comprises a long pivoted arm carrying a ball receiving pocket at its end into which the ball drops after it has completed its passage over the bagatelle board. The lever is 25 swung in an arc raising the ball to the top of the bagatelle board and then drops it through an orifice upon the swinging guideway. If the operator is successful in catching the ball in the movable cup, a spring 30 automatically returns the cup to its starting position permitting the ball to drop from the cup through an opening in the board down a chute and again out through an opening to the face of the bagatelle board 35 and onto the return runway which guides it back into the elevator. In the chute through which the ball passes in returning to the front of the bagatelle board is positioned a trigger actuated by the weight of the ball 40 to ring a gong thus signaling the success of the player.

Referring now to the particular embodiment, chosen to illustrate a preferred form of the invention, the numeral 20 indicates 45 the base of the cabinet or casing from which the opposite parallel sidewalls 21 and 22 extend upwardly and are connected by a top or cover 23. A rectangular face or front frame 24, within the opening of which is 50 mounted the bagatelle board 25, constitutes the front of the casing, a glass window 26 overlying the face of the bagatelle board and serving as an outer wall of the channel through which the playing ball descends. 55 A removable door 27 closes the rear of the casing giving access, to the mechanism and in the lower portion of the rear of the casing a removable door 28 is provided opening to a coin receptacle 29.

60 The coin released mechanism forms no part of the present invention, and, as it is fully described in our co-pending application Serial No. 82,927 filed March 8, 1916, and entitled coin controlled vending machine, we will refer to the same but briefly.

The coin released mechanism comprises a pair of plates 30 and 31 spaced apart on posts 32 and secured to brackets 33 extending rearwardly from the bagatelle board 25. A plate 34 is slidably mounted on the 70 front face of the inner plate 31 and at its inner edge carries a flange 35 which extends across the front of the opening between the two spaced apart plates. The manually operable mechanism comprises a hand lever 37 75 projecting outwardly from a vertically reciprocable bar 36 which is guidedly supported in outstanding brackets 38 formed integral with the back of the bagatelle board. The lever 37 extends through an opening 39 cut 80 in the front wall of the casing and covered by a vertically slotted plate 40. A shaft 41 journaled in the spaced apart plate 30-31 has a crank 42 formed on its front end engaging with the horizontal slot or guideway 85 43 formed in a side extension of the bar 36. Vertical reciprocation of the bar 36 will cause oscillation or partial rotation of the shaft 41, a spring 44 normally maintaining the bar 36 in its uppermost position. Secured on the shaft 41 is a downwardly extending crank 45 to which is pivoted a horizontal rod 46 guidedly supported in an opening in the wall 47 of a coin chute 48. Normally the rod 46 is free to pass through 90 the opening in the wall of the coin chute and through a registering opening 49 in the flange 35 of plate 34. In the event, however, of a coin being dropped into the chute 48, the same will serve as a lock or key to 95 obstruct the movement of rod 46 through the opening 49 and cause engagement between rod 46 and the flange 35 of the slideable plate 34, connecting these parts for movement by the hand lever 37.

A coin dropped into the slot in plate 50 positioned at the right hand upper corner of the face of the machine falls into the rearwardly and downwardly inclined chute 51. The coin passes from the rear end of coin 110 chute 51 to the vertical chute 52 which at its lower end bends inwardly into register with chute 48. Ratchet teeth 54 are formed on a sector integral with the lower end of arm 45 for engagement with the pivoted 115 dog 55 which prevents retrograde movement of the mechanism until it has nearly completed a full stroke in either direction. Spring 56 resiliently holds the dog in vertical position and a coil spring 57 resiliently 120 holds the plate 34 in its retracted position.

From the above it will be apparent that normally the hand lever 37 is free to move without initiating any operation of the mechanism but on a coin being deposited in 125 the chute and serving as a lock between the rod 46 and plate 34 the movement of the hand lever 37 will cause movement of the plate 34 to the right (looking at Fig. 3) to actuate the vending and game mechanism. 130

On the return of the sliding plate 34 to its initial position under the influence of spring 57 when the hand lever is released, the coin, freed from its frictional engagement between the rod 46 and flange 35 drops through the bottom of the chute 48 into an auxiliary chute 48' which leads into a recess or chamber 50'. This chamber is bounded by a back-wall 51' and at the front by a window 52' opening to the face of the bagatelle board and permitting observation of the coin from the front of the machine. The last dropped coin is held within the chamber 50' by a movable bottom 53' formed as a downwardly depending extension of the plate 34. As the plate is moved forward on a successive operation, the bottom 53' is moved from under the coin which drops into a chute 54' leading into the coin receptacle 29. As the plate 34 moves back into its initial position and the next coin is released, the bottom 53' again is positioned beneath the chamber 50' and this last coin then dropping through the channel 48' is held until the next operation of the machine.

Turning now to the vending mechanism which is one of the instrumentalities made operable upon the insertion of a coin, we have mounted a horizontal plate 58 near the bottom of the bagatelle board 25 upon rearwardly extending lugs 58' integral with the back of the board. A magazine or receptacle within which the articles to be vended, are contained, extends upwardly from plate 58 and comprises a pair of oppositely positioned channels 59 within which the articles are stacked and guided down through an opening 60 in the plate 58. Beneath this opening and spaced downwardly from the plate 58 is a second plate 61, the upturned sides 62 of which serve as guides within which reciprocates the carriage 63. The carriage is provided with a rectangular opening 64 corresponding to the plan area of the packages to be distributed and is normally maintained by means of spring 65, in position with the opening 64 out of register with the opening of the chute, but in register with the cut-away portion 66 in the lower plate 61. A lever 67 pivoted at 68 extends through slots in the upturned walls 62 and engages the carriage, its end projecting well beyond the vending mechanism for suitable operation. Oscillation of lever 67 causes reciprocation of carriage 63. When the mechanism is in the position indicated in Fig. 7 the lowermost of the packages within the chute 59 rest upon the table 69 of carriage 63. On the lever 67 being swung into its opposite extreme position, the opening 64 in the carriage will register with the opening in the chute and the lowermost of the stacked packages will drop into this opening. The spring then returns the carriage

into the position as shown in Fig. 7 and the package drops from the opening 64 in the carriage through the cut-away portion 66 of the under plate. The package thus ejected falls upon a guiding wall 70 which leads to a recess 71 opening through the bottom of the front wall of the casing at 72.

In Fig. 10, we have illustrated a charger by means of which the storage magazine 59 may be quickly and conveniently replenished. A tube 75 of a size permitting it to telescope within the magazine 59, is provided at its lower end with a pair of flat leaf springs 77 which extend slightly into the lower end thereof to engage the lowermost of a series of stacked packages 76 which may be conveniently inserted within tube 75, at the store or office of the operator. The attendant in charging the machine opens the rear door 27 which permits the withdrawal of a pin 78 which is slidable in a hole in top 23 and which locks in position a lid or cap 79 hinged to the top of the casing 23 as at 80. The lid 79 overlies the top of the magazine tube 59, and the operator then telescopes the tube 75 within tube 59 for its entire length. He then places a finger upon the upper end of the stacked packages 76 and withdraws the tube 75, the resistance of the springs 77 being sufficient to hold the stacked packages temporarily in place but insufficient to prevent their being transferred to the magazine 59 when tube 75 is withdrawn.

For the purpose of connecting the hand operated coin-released mechanism with the delivery mechanism, we have provided a lever 100 pivoted to the back of the bagatelle board as at 101 with its lower end extending through a slot 102 in plate 58 for engagement with the delivery carriage actuating lever 67. The upper end of the lever 100 is engaged by a lug 103 secured on the flange 35 of plate 34. When the plate 34 is connected to the hand lever, the lug 103 is pushed against the upper end of the lever 100 drawing the lower end of the lever to the left and actuating the delivery slide to deposit a package in the delivery chute. A latch lever 104 is pivoted as at 105 on the outer plate of the coin-released mechanism with its end adapted to be pressed by means of spring 106 into engagement with the upper edge of the outstanding lip 104' projecting from flange 35. When the flange is at the extreme right-hand position, the spring 106 forces the latch into engagement with the rear face of the lip 104' holding the plate 34 and flange 35 in this position until the latch is released. On the manually operated lever being returned to its starting position an arm 107 carried by shaft 41 and extending through opening 108 in the plate 30 drops down upon the rear end of lever 104.

and forces it out from engagement with the lip 104'. The plate 34 and consequently lever 100 then spring back into position under the influence of the delivery slide actuating spring 65.

The game mechanism of the apparatus partakes of the nature of a bagatelle board in which a steel ball 125 comprises the movable playing member. The bagatelle board 10 heretofore referred to and designated by the numeral 25 comprising the front of the casing within which the mechanism is inclosed and is provided with an outstanding peripheral rim 126 which spaces the flat surface 15 25 of the board rearwardly from the glass 26, a distance somewhat greater than the diameter of the playing ball. The front of the board is arranged with feed opening 127 in flange 126 at its upper central portion 20 through which the ball is discharged into the guide-ways and hazards. Immediately below the feed opening 127 we have provided a rocking guide member 128 having diverging channels 129, the center being somewhat higher than the ends and positioned immediately beneath the opening 127. The guide-way is carried on a shaft 130 journaled in the board as at 131 and carrying at the rear, behind the bagatelle board, a depending, weighting pendulum arm 132. Stop pins 133 project outwardly from the front of the board to limit the oscillatory movement of the member 128. A ball dropped through the orifice 127 falls upon the 30 oscillating member 128 and, depending upon the position which it happens to occupy at that time, will fall either to the left or right thereof, its course to the right or left being an indeterminate quantity over which the 35 operator has no control.

Immediately below the oscillating member 128, we have provided a pair of downwardly inclined runways 134 which extend inwardly from opposite sides of the board, 40 their inner ends being spaced apart to permit the ball to fall downwardly into a hazard comprising a plurality of spaced apart outwardly extending pins 135. Immediately below the hazard 135, a horizontal 45 slot is formed in the back wall 25 of the bagatelle board through which project a pair of arms 137 carrying at their outer ends a cup 138, in which the playing ball may be caught. The arms 137 with the cup 138 50 are longitudinally slidable across the face of the machine through the slot 136 by the manual operation of a knob or handle 139 which projects outwardly through the front of the casing near the lower left hand corner thereof. The knob 139 is mounted on the outer end of a shaft 140 which passes through the frame to the rear of the board and carries an upwardly extending lever 60 65 141. This lever in turn is connected by means of a link 142 with the lower end of the lever

143 pivoted at 144. The upper end of lever 143 is provided with a slot 145 which engages a pin 146 extending rearwardly from a carriage 147 transversely slidable across the board on a guide-rod 148. An arm 149 70 projects upwardly from the carriage and bears against a guide-rib 150. The basket or cup carrying arms 137 are connected to the carriage 147 and the operator may therefore slide the carriage 147 with its ball 75 catching cup 138 to the left or right across the face of the machine by oscillating the handle 139. A spring 153 returns the ball catching mechanism to its initial position shown in Fig. 2, a stop 164 engaging lever 80 141 to limit its movement.

Directly below the slot 136 is a runway 151 extending across the entire width of the machine and inclined downwardly to the left (looking at the front of the machine), 85 so that a ball falling through the hazard will drop upon the runway and be returned through an orifice 152 at the lower left hand corner of the runway to the rear of the board for subsequent elevation 90 to the opening 127.

In the event the operator is successful in catching the ball 125 within the cup 138 of the movable member the spring 153 returns the carriage with its caught ball to 95 its initial position as shown in Figs. 1 and 2. When in this position, the rear open face of the cup 138, which heretofore has been closed by coöperation with the bagatelle board, now registers with an opening 154 100 in the face of the board communicating with a short, vertical channel 155 formed by an offset portion 156 of the board and a plate 157 which overlies the rear thereof. The ball dropping down through the channel 155 is again returned to the front of the machine through an opening 158 which leads the ball back upon the runway 151. In passing through the channel 155, the ball strikes an arm 159 which projects into the channel and forms one end of a lever 160 pivoted as at 161 upon an extension of plate 157 and carrying upon its lower, depending end a hammer 162 for engagement with a gong or bell 163. By means of this apparatus the success of the operator in 110 catching a ball is indicated by a ringing of the gong.

The elevator comprises a long arm 178 pivoted upon the shaft 41 and carrying at 120 its outer end a cage or ball receiving cup 179. The front side of the cup is open for coöperation with the opening 152 to receive a ball which rolls rearwardly through this opening after the play has been completed. The opposite end of the lever 178 carries a short, downwardly extending projection 180 which is adapted to be engaged by the pin 181 carried on the sliding plate 34. As the plate is actuated by the operator, 130

a coin having been deposited and serving to connect the operating mechanisms, the outer free end of the lever 178 is elevated in an arc about the shaft 41 as a center. The end 5 of the lever bears against an arcuate rib 182 formed integral with the back of the bagatelle board and terminating at its top in a flanged channel 183 which leads down to the opening 127 through which the ball is 10 dropped for commencement of play. The ball carrying cage 179 on the end of the elevator arm 178, is open at its front face to receive the ball through the opening 152 and after it has been elevated up to the channel 15 183, permits the ball to roll by gravity out of the cage into the channel and thence through the aperture 127. Throughout the passage of the ball, from lower to upper position, the ball is prevented from rolling 20 out of the cage opening by its coöperation with the back of the bagatelle board.

In order to prevent the playing ball 125 from rolling back through the orifice 152, in the event the elevator has not been 25 turned to its starting position, we provide a stop 175 carried on the end of a lever 176 pivoted as at 177. The left-hand end (looking at Fig. 2) of the lever is heavier than the opposite end so that the stop 175 is normally held upwardly to close the rear of 30 the opening 152.

The lower side of the ball cage 179 is arranged to coöperate with the stop 175 so that when the cage is lowered into the position shown in Fig. 2, the stop is pushed 35 down and out of the way to permit the ball to roll through the opening 152 into the elevator. As soon as the elevator commences its upward movement, the weight of the 40 outer end of lever 176 raises the stop 175 into position to prevent a ball from dropping through the opening 152 until the elevator has been returned to its starting point.

A lock mechanism comprising a connection 45 between the package magazine and the coin-receiving slot, is provided to prevent the insertion of a coin after the package magazine has been emptied. This apparatus consists of a long arm 200 pivoted as at 201 50 at a point near the upper end of the magazine and positioned with its lower end arranged to register with the vertical opening in the magazine between the two side-channels. The upper end of the rod 200 beyond the pivot point is bent over to one 55 side as at 202 and connects with a short lever 203 pivoted as at 204 and positioned so that its free, outer end may be dropped into the channel or guide 51 at a point immediately 60 behind the coin-slot in the plate 50. When the magazine is filled with packages, the arm 200 is held by the packages in the position shown in Fig. 2, the lower end of the arm extending to a point near the lower 65 end of the magazine. The arm when in this

position holds the stop lever 203 in elevated position as shown in Fig. 8. When the magazine becomes exhausted and the packages no longer hold the arm 200 in the position shown in Fig. 2 its lower end swings to 70 the right permitting the stop lever 203 to drop preventing the passage of a coin into the coin chute.

To make the game more interesting, we have attached the figure of a base-ball player 75 205 upon the oscillating chute 128 and the figure of another player 206 upon the ball catching cup 138. The figure 205 represents a batter and the figure 206 represents a player with arms extended, as if in the 80 act of catching a ball. Other suitable figures may be used in place of the ball players.

Whereas we have illustrated and described a particular embodiment of the invention, it will be obvious to those skilled 85 in the art that various changes may be made therein, without departing from the spirit of the invention or the scope of the appended claims.

Having described our invention, what we 90 claim is:—

1. The combination with a coin-released vending mechanism, of a game apparatus, a playing ball, a ball-operated signal mechanism, a manually operated ball catching 95 mechanism; a guide-way for leading a caught ball to said ball operated signal mechanism and means for elevating the ball upon the manual operation of the machine.

2. The combination with a coin-released vending mechanism, of a game apparatus, a playing ball, a ball-operated signal mechanism, means associated with the vending mechanism for starting the ball in play, a 105 manually operated ball catching mechanism; means for leading a caught ball to said ball-operated signal mechanism, manual means to instigate operation of the machine and means operable by said manual means for 110 elevating the ball.

3. The combination with a coin-released vending mechanism, of a game apparatus, a playing ball, a ball operated signal mechanism, means associated with the vending 115 mechanism for elevating the ball to starting position at the top of the game apparatus; manually operable means for controlling said ball-elevating mechanism; a manually operated ball catching mechanism, and 120 means for leading a caught ball to said ball operated signal mechanism.

4. The combination with a manually operable coin-released mechanism, of a game apparatus comprising a bagatelle board having 125 openings at top and bottom portions thereof, a playing ball, and a pivoted arm connected with the coin-released mechanism and having a ball receiving pocket formed in the free end thereof adapted to register with 130

the lower opening to receive the ball, and with the top opening to start the ball in play.

5. The combination with a coin-released mechanism, of a game apparatus comprising a bagatelle board having openings at the top and bottom portions thereof, a playing ball, a pivoted arm having a ball receiving pocket formed in the free end thereof adapted to 10 register with the lower opening to receive the ball, and with the upper opening to start the ball in play, ball operated signal mechanism, and means connecting the arm and coin-released mechanism.

15 6. The combination with a coin-released mechanism of a game apparatus comprising a bagatelle board having openings at the top and bottom portions thereof, a playing ball, a pivoted arm having a ball receiving opening in the free end thereof adapted to register with the lower opening to receive the ball and with the upper opening to start the ball in play, a ball operated signal mechanism, a manually controlled ball catching device, 20 25 means for leading a caught ball to the ball operated signal mechanism, and means connecting the arm and coin-released mechanism.

7. The combination of a coin-released mechanism, a game apparatus comprising a bagatelle board having openings in the top and bottom portions thereof, a playing ball, means connected with the coin released mechanism for elevating the ball from the 30 35 bottom to the top opening, hazards through which the ball falls in its play, and a movable ball receiving guideway for varying the path of ball travel.

8. The combination of a coin released mechanism a game apparatus comprising a bagatelle board, a playing ball, means connected with the coin released mechanism for starting the ball in play, hazards through

which the ball falls, and a freely movable ball deflector having diverging guideways 45 for varying the path of ball travel.

9. The combination of a coin-released mechanism, a game apparatus comprising a bagatelle board having openings in the top and bottom portions thereof, a playing ball, 50 means connected with the coin-released mechanism for elevating the ball from the bottom to the top opening, and a freely movable ball receiving guideway sloping downwardly to each side from its center for varying the path of ball travel.

10. The combination of a coin released mechanism, a game apparatus comprising a bagatelle board having openings in the top and bottom portions thereof, a playing ball, 60 means connected with the coin released mechanism for elevating the ball from the bottom to the top opening, and an oscillatable ball receiving guideway sloping downwardly to each side from its center for varying 65 the path of ball travel.

11. The combination of a coin-released mechanism, a game apparatus comprising a bagatelle board having openings in the top and bottom portions thereof, a playing ball, 70 means connected with the coin released mechanism for elevating the ball from the bottom to the top opening, a freely oscillatable ball reflector pivoted directly beneath the top opening and having diverging guideways sloping downwardly to each side from its center, hazards positioned beneath the deflector, a ball operated signal mechanism, a manually controllable ball catching device 75 movable across the board beneath the hazards, and means to deliver a caught ball to the ball operated signal mechanism.

In testimony whereof we hereunto set our hands.

JOSEPH PAUPA.
GUSTAV F. HOCHRIEM.
